Lorren E. Hogue.
BY John H. Fowler.

ATTORNEY

UNITED STATES PATENT OFFICE.

LOVREN E. HOGUE, OF GREENVILLE, MERCER COUNTY, PENNSYLVANIA.

INJECTOR.

SPECIFICATION forming part of Letters Patent No. 408,715, dated August 13, 1889.

Application filed March 15, 1889. Serial No. 308,431. (Model.)

To all whom it may concern:

Be it known that I, LOVREN E. HOGUE, a citizen of the United States, residing at Greenville, in the county of Mercer and State of Pennsylvania, have invented certain new and useful Improvements in Injectors for Steam-Boilers; and I do hereby declare that the following is a full, clear, and exact description of the same, reference being had to the annexed drawing, making a part of this specification, and to the letters and figures of reference marked thereon.

This invention relates to certain new and useful improvements in injectors of that class known as "single-barrel" injectors, with the exception that this is not a restarter.

The invention consists in the peculiarities of construction and the combinations, arrangement, and adaptation of parts, all as more fully hereinafter described, shown in the drawing, and then particularly pointed out in the appended claim.

The invention is clearly illustrated in the accompanying drawing, which represents a central section through my improved injector.

Referring now to the details of the drawing by letter, A designates the shell; B, the steam-inlet; C, the water-inlet; D, the overflow, and E the connection to the boiler. The end of the shell adjacent to the steam-inlet is formed with a recess *a*, in which is fitted the annular flange *b* on the end of the nozzle *c*, formed with a steam-chamber *d*, and within this nozzle, with its annular flange *e* on it seated in

a groove therein, is the tube *F*, which extends 35 through a suitable opening in the other end of the nozzle *c* and is provided in its said flange with the perforations *f*, which afford communication between the steam-chamber *G* and that within the nozzle *c*.

His the tube, having its inner end adapted 40 to embrace the tapered end of the tube *F*, as shown, and near its other end provided with a valve *g*, which finds a seat against the seat *h* within the shell, as shown.

i is a passage through which the steam passes to exhaust the air from the space *C* or water-supply pipe.

What I claim as new is—

In an injector, the combination, with the 50 shell *A*, formed with the seat *h*, of the nozzle *c*, the tube *F*, extended through said nozzle and having tapered end, as shown, with a passage *i* around the tube at the end of the nozzle *c*, the tube *H*, having its inner end embracing the tapered end of the tube *F* and 55 guided by the walls forming said seat *h*, and the valve on the other end of the tube *H* and bearing on said seat, substantially as shown and described.

In testimony that I claim the above I have hereunto subscribed my name in the presence of two witnesses.

LOVREN E. HOGUE.

Witnesses:

R. MAXWELL,
W. MAXWELL.
